EXPANSION CHANNEL

Jon W. Lee, Campbell, Calif., assignor to Owens-Corning Fiberglas Corporation, a corporation of Delaware
Filed Apr. 17, 1963, Ser. No. 273,760
6 Claims. (Cl. 98—40)

This invention relates to an expansion channel member designed to cooperate with air distribution duct assemblies as part of a grid work for the support of sub-ceiling elements at a level beneath the main ceiling of an enclosed space. An expansion member embodying the invention presents to the eye a configuration quite similar to that of the air distribution member of the duct assembly, supports some parts of the sub-ceiling elements, or lighting fixtures and the like and accommodates for expansion and contraction of the entire sub-ceiling grid work including conventional "T-bars."

In co-pending application of Lee and White, Serial No. 231,897 filed October 22, 1962, there is disclosed an air distribution duct assembly comprising an elongated diffuser bar and a continuous air supply duct, the two being in communication with each other throughout their lengths, and the diffuser bar functioning both to discharge air from the supply duct into the space being treated and to support the elements of a dropped or sub-ceiling. In such a construction the air supply duct is located above the diffuser bar and hidden by the sub-ceiling elements. Such air distribution duct assemblies may extend from end to end of an enclosed space and there may be more than one of such duct assemblies in the space. For example, in a large space such as an engineering or general office, measuring, say, 200 by 100 feet in size, the duct assemblies may extend the full length of the room, be spaced ten or twenty feet from each other so that the entire 200 by 100 foot ceiling would include some five to ten of the duct assemblies extending parallel to each other. The ceiling grid work would also include cooperating, transversely extending "T-bars" for the support of the various elements from which the sub-ceiling is fabricated, such as acoustical tile, and other surface elements or functional devices such as lighting fixtures. When there is a substantial differential between the temperature of ambient air in the plenum space above the sub-ceiling and the temperature of the conditioned air delivered through the air distribution duct assemblies and, more particularly, in the areas of the plenum chamber where lighting fixtures and the like are located, considerable expansion and contraction of the metallic "T-bars" or of the air distribution duct assemblies may take place under varying conditions.

The problem caused by expansion and contraction of these various metallic elements has been considered and attempts to solve it have been met by the use of slip joints between contiguous lengths of the air distribution duct assemblies or between lengths of the "T-bars" and also at the junctions between the "T-bars" and the air distribution duct assemblies. Slip joints in these locations are less than satisfactory because the shapes of the two elements in telescoping relationship may not remain constant and the joints may not slip freely, leaving openings or causing crumpling in some severe circumstances.

It is the principal object of the present invention to provide an expansion member for use in a grid work in the support of a sub-ceiling, the grid work comprising continuous lengths of "T-bars" and of air distribution duct assemblies by which conditioned air is delivered or returned from the space beneath the sub-ceiling.

This and more specific objects and advantages of the instant invention will be better understood from the

2

specification which follows and from the drawings in which:

FIG. 1 is a fragmentary view in perspective of an enclosed space provided with a sub-ceiling incorporating sub-ceiling elements supported by grid work comprising air distribution duct assemblies, "T-bars" and expansion members embodying the invention;

FIG. 2 is a fragmentary, vertical, cross section of an air distribution duct assembly of the type disclosed in the mentioned Lee and White application, and which is illustrated as being employed in the grid work shown in FIG. 1; this assembly not constituting part of the instant invention but being included for purposes of understanding; the cross section being shown on a substantially enlarged scale with respect to the scale of FIG. 1;

FIG. 3 is a fragmentary, vertical sectional view of an expansion member embodying the invention, the view being similar to FIG. 2 and illustrating how the expansion member functions for the support of sub-ceiling elements and for connection with transversely extending "T-bars" of the sub-ceiling support grid;

FIG. 4 is a fragmentary view in perspective illustrating how a right angle junction of two runs of an expansion member embodying the invention are connected to each other and further illustrating a manner of connection of "T-bars" to such expansion member;

FIG. 5 is a fragmentary view in perspective, and on a greatly reduced scale, illustrating the junction between an air distribution duct assembly as illustrated in FIG. 2 and an expansion member as illustrated in FIG. 3; and

FIG. 6 is a fragmentary, vertical sectional view, taken along the line 6—6 of FIG. 5 and being shown on an enlarged scale.

An enclosed space such as that fragmentarily illustrated in FIG. 1 in a modern building usually is defined by a floor, generally indicated by the reference number 10, walls 11 and a false or sub-ceiling generally indicated in FIG. 1 by the reference number 12. The sub-ceiling 12 is usually dropped down from the main ceiling of the room 13 which is also the underside of the floor of the next higher level or may be the main ceiling of the building, as for example, the roof structure of a one story building. The upper main ceiling is not shown in FIG. 1 except fragmentarily by the portion indicated by the reference number 13 and often is of reinforced concrete or the like thus constituting a main structural element of the building. The space between the underside of the structural ceiling 13 and the sub-ceiling 12 is referred to as a plenum space and is utilized in modern buildings for conduits for lighting equipment, power lines, telephone and other communication systems, heating ducts, air conditioning ducts and the like.

In the illustration of FIG. 1, two air distribution duct assemblies, generally indicated by the reference numbers 14 are shown as being suspended by hanger wires 15 from fragmentary indications of the upper structural floor 13 and as extending transversely across the space under consideration. Each of the air distribution duct assemblies (FIG. 2) consists of a diffuser bar, generally indicated by the reference number 16, and comprising a pair of spaced side bars 17, an air duct 18 comprising a resilient sheet material jacket 19 and an insulating layer 20 laminated therewith and located interiorly of the jacket 19. The side bars 17 form an elongated conduit, open at the top and bottom for the passage of air vertically therethrough. The entire air distribution duct assembly 14 is supported, as mentioned, by the hanger wires 15 which are engaged with support tabs 21, the tabs 21 being inserted in suitable slots near the upper ends of the side bars 17. At the upper outer sides of the side bars 17, there are located hook means 22 which cooperate with flanges 23 at the longitudi-

nal edges of the jacket 19 for retaining the duct 18 in place on the diffuser bar 16. At the lower ends of the side bars 17, there are outwardly turned flanges 24 which are utilized for the support of edges of sub-ceiling elements such as insulating ceiling tiles, of which one is indicated by the reference number 25. The diffuser bar 16 is connected to transversely extending, inverted "T-bars" 26 (see also FIG. 1) by bent assembly clips 27. The open bottom of the air passageway between the bars 17 may be partially obstructed by a diverter 28.

The construction thus far described with respect to FIG. 2 is that disclosed and claimed in the above referenced Lee and White application and does not, in itself, constitute a part of the instant invention. The cooperation between the air distribution duct assemblies 14 and the "T-bars" 26 is also fully discussed in the Lee and White application.

As earlier mentioned, a sub-ceiling assembly such as that illustrated in FIG. 1, may also comprise lighting fixtures such as the row of lighting fixtures indicated by the reference number 29 and these lighting fixtures 29, as well as the sub-ceiling elements 25, are supported by the flanges 24 on the air distribution duct assemblies 14 and similar flanges 30 on the T-bars 26. As can be seen by reference to FIG. 2 the flanges 24 of the diffuser bar 16 of the air distribution duct assemblies 14 and the flanges 30 of the "T-bars" 26 are on the same horizontal level so that the ceiling elements 25 and the lighting fixtures 29 may be supported by these flanges 24 and 30 all in the same plane to present a flush, apparently continuous surface on the sub-ceiling 12.

As earlier mentioned, because of the differential between the temperature of the conditioned air which is supplied through the duct assemblies 14 and the usually much higher temperature within the plenum space itself above the sub-ceiling 12, especially in the vicinity of the lighting fixtures 29, the duct assemblies 14, the T-bars 26 or other transversely extending T-bars such as those indicated by the reference number 31 in FIG. 1, elongate and shorten during changing conditions and to different degrees. In a large room such as that illustrated in FIG. 1, where the ceiling grid work comprises all of the elements illustrated therein, it is particularly necessary that means be provided for accommodating for this expansion and contraction without distorting any of the ceiling support elements, the sub-ceiling elements or the lighting fixtures.

Two expansion members 32 and 33 are shown in FIG. 1 and illustrated in greater detail and on an enlarged scale in FIGS. 3-6. Each of the expansion members 32 or 33 consists of a pair of vertically extending side members 34 at the lower end of which there is located an outwardly directed horizontal flange 35. Each of the side members 34 also has on its outer side a pair of vertically spaced slots 36 which are separated a distance from each other such that they will snugly receive the upper and lower edges of a groove engaging end portion 37 of an assembly clip 27. The slots 36 are spaced from each other and spaced relative to the level of the flanges 35 the same as similar slots 38 in the side bars 17 of the diffuser bar 16. This identity of vertical spacing between the side members 34 of the expansion members 32 and 33 and the side bars 17 of the diffuser bars 16 results in all of their flanges 24 and 35 and also the flanges 30 of the "T-bars" 26 lying in the same horizontal plane.

The two side members 34 of the expansion members 32 and 33 are connected to each other by an elongated vertically extending bifurcated member or "wishbone" 39. The lower edges of each arm of the wishbone 39 have integral ribs 40 which are slidingly inserted into slots 41 formed at the inner sides of the side members 34. The arms of the bifurcated member 39 are preferably flexible. At its upper ends, the wishbone 39 has a web 42 which extends throughout its length and through

which there is perforated a series of holes 43 for engagement by hanger wires 15.

Where two or more of the expansion members 32 or 33 intersect each other, they are connected by a cross member 44 (see FIG. 4 particularly). The cross member 44 consist of four pairs of short lengths of the side members 34, each pair being designated 34a, 34b, 34c and 34d in FIG. 4. Intersecting ones of the pairs of short side members 34a, b, c, and d, for example those indicated by the reference numbers 34b and 34c in FIG. 4 are connected to each other by angle clips 45 at their mitered corners. Each arm of the angle clip is mounted in the vertically spaced outer slots 36 of a respective one of the side members 34b and 34c in lengths of "wishbones" indicated by the reference numbers 39a, b, c, and d in FIG. 4 are engaged in the inner slots 41 of the side members in the pairs 34a, b, c, and d. As shown in FIG. 4, wishbones or bifurcated members 39a and 39c are longitudinally spaced from one another. Similarly, bifurcated members 39b and 39c are also longitudinally spaced from one another. The longitudinal spacing between longitudinally aligned bifurcated members of the cross member 44 provides room for expansion between the various elements making up the cross member 44. The cross member 44 is connected to the long lengths of the expansions members 32 and 33 by flat connecting plates 46 which are inserted in the vertically spaced pair of the slots 36 as illustrated in FIG. 4.

In a large area such as that shown in FIG. 1, provision is also made for intersections of the expansion members 32 or 33 with the air distribution duct assemblies 14 and such an intersection is illustrated in FIGS. 5 and 6. Because the levels of the various slots and flanges such as the flanges 24 on the diffuser bars 16 and 35 on the expansion members 32 and 33 must be the same, it is necessary to accommodate the duct 18 by cutting away a portion of the "wishbone" 39 and web 42 of the expansion member, for example, the expansion member 32, with which it intersects. As illustrated in FIGS. 4 and 6, an arcuate notch 47 is cut in the upper portion of the wishbone 39 and web 42 and the duct 18 has an exterior jacket or tubular junction plate 48 snapped around its exterior at the intersection.

What I claim is:

1. In a sub-ceiling support grid work having inverted T bar elements, diffuser elements of air distribution duct assemblies and hangers for suspending said grid work at a certain level below the main ceiling of a room and in which said T bar elements and air distribution diffuser elements have oppositely directed horizontal flanges all lying at the same level for supporting sub-ceiling elements, an expansion channel for cooperation with said grid work elements comprising, in combination a pair of laterally spaced, vertically extending elongated side members an outwardly directed flange on the lower portion of each side member, an elongated bifurcated member having downwardly extending spaced arms and a top center web, means on said web for suspending said bifurcated member from the main ceiling and cooperating engageable means on said side members and the lower parts of said arms for supporting said side members.

2. A sub-ceiling support grid work, comprising (1) diffuser elements of air distribution duct assemblies, each of said diffuser elements consisting of a pair of elongated, laterally spaced, side bars forming an elongated conduit open at the bottom for the passage of air therethrough, an outwardly directed sub-ceiling support flange on each of said side bars at its lower end, aligned, vertically spaced means forming an elongated assembly clip groove on the outer side of each of said side bars for the reception and retention of assembly clips, (2) inverted T elements, sub-ceiling support flanges on said

inverted T elements similar in size and appearance to said flanges on said diffuser elements (3) an expansion element comprising (a) a pair of elongated, laterally spaced side members forming an elongated conduit open at the bottom, (b) an outwardly directed sub-ceiling support flange on each of said side members similar in size and appearance to said flanges on said T elements and said diffuser elements, (c) aligned, vertically spaced means forming an elongated groove on the outer side of each of said side members of a size for the reception and retention of assembly clips, (d) an elongated bifurcated member consisting of two downwardly extending, spaced legs and a central web defining a closed top for the space between said legs, (e) cooperating means on said side members and on said legs of said bifurcated member for supporting said side members in a lateral spacing corresponding to the lateral spacing of said side bars of said air distribution diffuser elements, (4) means for supporting said inverted T elements, said diffuser elements and said expansion element beneath the main ceiling of a room with their support flanges at the same level, (5) and assembly clips having at least one groove engaging portion and a T bar engaging portion extending outwardly from said groove engaging portion, said clips engageable in the grooves of said side bars and said side members for retaining said T elements, said diffuser elements and said expansion element in a reticulated open grid work with different elements in perpendicular relationship.

3. An expansion channel according to claim 1 and means for supporting the T bar elements of the sub-ceiling support grid work, said means comprising, a plurality of assembly clips having at least one groove engaging portion and a T bar engaging portion extending outwardly from said groove engaging portion, each of said laterally spaced elongated side members defining, on its outer side, a pair of vertically spaced opposed assembly clip slots for receiving said groove engaging portion of said assembly clips.

4. A sub-ceiling support grid work, according to claim 2, including intersection means for connecting two intersecting expansion elements, said intersection means comprising four pairs of short lengths of said side members, a first pair of said side members being longitudinally aligned with and spaced from a second pair of said side members, a third pair of said side members being longitudinally aligned with and spaced from a fourth pair of said side members, said third and fourth pair of said side members abutting and being perpendicular positioned with respect to said first and said second pairs of said side members, an angle clip having perpendicularly extending arms mounted in such elongated grooves of abutting ones of said side members, a bifurcated member mounted in each of said pairs of side

members, whereby longitudinal aligned ones of said bifurcated members defined therebetween an expansion space, and a connecting plate mounted in such elongated groove of each of said members extending beyond the free end of said side member, whereby said connector plate may be inserted in an outer elongated groove of an adjoining expansion element of such grid work.

5. An expansion channel cross member, comprising, 10 in combination, four pairs of elongated, laterally spaced side members, each of said side members having an outwardly directed sub-ceiling support flange at its outer lower edge, each of said side members defining a pair of longitudinally extending, aligned and vertically spaced 15 grooves on its outer side, a first pair of side members being longitudinally aligned with and spaced from a second pair of said side members, a third pair of said side members being longitudinally aligned with and spaced from a fourth pair of said side members, an angle clip having perpendicularly extending arms mounted in such vertically spaced grooves of abutting ones of said side members, an elongated bifurcated member, consisting of two downwardly depending spaced legs and a central wall extending between the top of said legs, 20 mounted in each of said pairs of said side members, whereby longitudinally aligned ones of said bifurcated members defined therebetween an expansion space, cooperating means on said side members and on said legs of said bifurcated members for supporting said side 25 members in a predetermined lateral spacing, and means on each of said pairs of said side members for connecting said pairs of side members to an adjoining element of a grid work.

6. In a sub-ceiling support grid work having inverted 30 T bar elements, diffuser elements of air distribution duct assemblies and hangers for suspending said grid work at a certain level below the main ceiling of a room and in which said T bar elements and air distribution diffuser elements have oppositely directed horizontal flanges 35 all lying at the same level for supporting sub-ceiling elements, an expansion channel for cooperation with said grid work elements comprising in combination a pair of laterally spaced, vertically extending elongated side members, an outwardly directed flange on the lower portion of each side member, an elongated flexure member having downwardly extending spaced arms and a top center web, means on said web for suspending said flexure member from the main ceiling and cooperating 40 engaging means on said side members and the lower parts of said arms for supporting said side members.
